UNITED STATES PATENT OFFICE.

ADAM H. SULSER, OF WASHINGTON, DISTRICT OF COLUMBIA.

DOOR CLOSING AND CHECKING DEVICE.

1,019,857.

Specification of Letters Patent. Patented Mar. 12, 1912.

Application filed October 13, 1911. Serial No. 654,556.

To all whom it may concern:

Be it known that I, ADAM H. SULSER, a citizen of the United States, residing at Washington, in the District of Columbia, have invented new and useful Improvements 5 in Door Closing and Checking Devices, of which the following is a specification.

My invention relates to improvements in door closers and checks, and the object of 10 the invention is to provide a door closer which can be easily manufactured, quickly assembled or taken apart for repairs, and which may be applied to a right-hand, left-hand or a swinging door at will, the same 15 operating with equal effectiveness irrespective of the swing of the door.

It is also an object of my invention to provide a checking mechanism on the swinging arm of the closing mechanism which 20 will operate to check the closing movement of the door whether the latter be swung to the right or to the left, the combined mechanisms making a compact, effective, and neat appearing closing and checking device.

Referring to the drawings furnished and forming a part of this specification: Figure 25 1 is a top or plan view of a combined door closer and checking device illustrating one embodiment of my invention. Fig. 2 is a 30 side view thereof. Fig. 3 is a bottom view of the rear portion of the device. Fig. 4 is a central longitudinal section through the closing and checking mechanism. Fig. 5 is a section on line 5—5 of Fig. 4. Fig. 6 is a 35 front view of the supporting bracket. Figs. 7 and 8 are side and bottom views respectively, of the sprocket wheel which is mounted on the supporting bracket of the device, and Figs. 9 and 10, are top and side views, 40 respectively, of the sleeve to which the inner end of the controlling spring is attached.

The device as a whole includes a bracket A, an arm B pivotally secured thereto, a checking mechanism carried by said arm, 45 and an adjustable link C pivotally connected to the outer end of the arm B and secured at its opposite end, preferably by a universal joint d, to a bracket D. The device is secured to a door and its casing by means of 50 the brackets A and D, the former being secured to the door at or near its upper edge, and the latter to the casing above the door, as in prior devices of similar type.

The bracket A is provided with an up- 55 right stud or spindle a on which is jour-

naled a box or casing E, the latter being provided with a cover e, which is adjustably but non-rotatively, secured to the casing by a screw e'. Said screw is tapped in the rim of the cover so that its inner end will engage 60 with any one of a series of holes e², (see Fig. 4), the cover being thereby held in any desired radial adjustment with respect to the casing. Housed within the casing E is a spiral spring F which operates to return the 65 arm B to normal position whenever it is moved in one direction or the other by the swinging movement of the door, said spring having its outer end f connected to the casing E and its inner end f' connected to a 70 sleeve G which is also journaled on the spindle a. The outer end f of the spring is made in the form of a hook which enters a slot e³ in the casing E, and a similar hook is formed at the inner end f' of the spring which enters a slot g in the sleeve G, so that the 75 spring tends to rotate the casing and sleeve in opposite directions. The casing E and sleeve G are free to be rotated against the action of the spring, but their movements by 80 the spring are limited by stops. The stop for the casing consists of a pin a', which for purposes of adjustment, may be inserted in any one of a series of holes e⁴ in the bottom wall of the casing, and which operates 85 against the bracket A to limit the movement of the casing, as clearly shown in Fig. 3. The pin a' is preferably mounted or made integral with a swinging arm a³ mounted on the underside of the bracket concentrically 90 with the stud or spindle a. Said arm is provided with a knurled handle or knob a⁴ and also with a stem a⁵ occupying a recess or hole a⁶ formed in the underside of the bracket. The upper end of the stem a⁵ is 95 provided with a head a⁷ which is engaged by a spiral spring a⁸ for holding the stem and arm a³ in elevated position with the pin a' in engagement with the casing E, the lower end of said spring bearing upon a 100 plate a⁹ secured to the bracket by screws, as clearly shown in Fig. 4. By means of the knob a⁴ the pin a' may be pulled down out of engagement with the casing E and then swung around opposite another hole e⁴ into 105 which it will be drawn and held by the spring a⁸ as will be readily understood.

The sleeve G projects through the cover e of the casing and is provided at or near its upper end with an integral collar g' carry- 110

ing a projection or stop g^2 which engages with a similar stop h projecting from the hub h' of a sprocket H, the latter being fixedly secured to the upper end of the stud 5 or spindle a . The hub of the sprocket wheel H is provided with a square opening h^2 which fits the squared end a^{10} of the stud a , a screw a^{11} operating to hold the sprocket to the spindle, as best illustrated in Fig. 4.

10 It will thus be seen that the stops g^2 and h operate to limit the movement of the sleeve G by the spring F but that said sleeve is free to be rotated by the arm B against the tension of the spring as will now be explained.

The arm B is provided with a hub b journaled on the sleeve G between the collar g' and the cover e of the spring casing, said arm being free to be swung in either direction around the axis of the stud a , but carries the sleeve against the tension of the spring F when moved in one direction, and carries the casing E against the spring when moved in the opposite direction. The collar 20 g' of the sleeve G is provided with a projection g^3 which is engaged by the arm B when the latter is moved in one direction so as to move the sleeve G against the tension of the spring, the latter acting through said 25 sleeve to return the arm to normal position. The cover e of the spring casing is likewise provided with a stop or projection e^5 which is engaged by the arm B when moved in the opposite direction, so as to move the casing 30 against the spring, which will act through the casing to return the arm to normal position.

When it is desired to change or adjust the tension of the spring, the arm B is 40 moved in the direction to rotate the spring casing. This will cause the stop pin a' to be moved out of engagement with the bracket A, when it may be moved from one hole e^4 to another as already explained. 45 This will change the position of stop e^5 on the cover e with reference to the arm B, and to readjust said stop it is only necessary to release the engagement of the screw e' with the body of the casing, rotate the cover to 50 adjust the stop, and again set the screw in the proper hole e^2 , as will be readily understood.

I have devised a checking mechanism for 55 use in connection with the closing mechanism above described, which will operate to check the closing movement of the door regardless of the direction in which the door may swing. This mechanism is mounted on or within the arm B, the latter being made 60 in the form of a hollow tube closed at both ends and having an enlarged central chamber b' for the reception of the operating mechanism. The opposite ends of the arm 65 constitute cylinders in each of which is mounted a reciprocating piston J, J' the

latter being made to closely fit the interior of the cylinders and being provided with a passage j through which liquid may pass when the cylinders are moved inwardly toward each other. The passages j are each controlled by a ball valve j' which operate to close the passages when the cylinders are moved outwardly, or away from each other. The pistons are connected by pivotally mounted rods k, k' , to oppositely arranged 70 cranks k^2 and k^3 , the latter being formed on opposite sides of a disk K, rotatively mounted in the chamber b' . Said chamber is circular and the disk K is made to loosely fit the interior thereof with its outer edge 75 resting on a shoulder or ledge b^2 . The crank pin k^2 projects downwardly from the disk K through the end of the piston rod k and also through the end of a link L which is pivotally mounted on a stud l concentric 80 with the axis of the disk K; said link serving to hold the rod k in place on the crank pin. The crank pin k^3 projects upwardly from the disk K through the end of the piston rod k' and is provided with a squared end k^4 which enters a square hole in a disk 85 m which is preferably formed integral with a shaft M, the crank and disk m being secured together by a screw m' , all as clearly 90 shown in Fig. 4. The chamber b' is provided with a cover b^3 through which the shaft M projects, a stuffing box m^2 being provided for preventing the escape of liquid with which the chamber b' and the cylinders are filled, said cover being secured to 95 the circular wall of the chamber b' by means of screws, as clearly shown.

A sprocket wheel N is fixed to the upper end of the shaft M, and is connected by an endless chain O with the sprocket H, which 100 is fixed to the bracket A and serves to rotate the shaft M whenever the arm B is moved relatively to the bracket A, the direction of rotation of the shaft being governed by the direction of movement of the arm B. The cylinder and the chamber b' are filled with glycerin or other suitable liquid, so that when the arm B is moved by the swinging movement of the door, the shaft M will be rotated in one direction or the other and will cause the cranks k^2 and k^3 to pull the pistons J and J' inwardly toward each other, the liquid passing freely 110 through the passages j from the rear to the forward or compression ends of the cylinders. When the arm B starts to return to normal position, the ball valves j' will close the passages j so that the liquid in the forward or compression ends of the cylinders 120 will operate to retard the outward movement of the pistons and thus operate to check the return movement of the door. A small by-pass P is provided in the walls 125 of the cylinder for the slow passage of the liquid from the compression end of the cylinder 130

inder to the rear end of the pistons, these passages being controlled by a screw p' in a well known manner.

Having thus described my invention, what I claim as new and desire to secure by Letters Patent is—

1. In a door closing device, the combination of a supporting bracket, an arm pivotally connected thereto, a spring casing rotatably mounted on said bracket, a spring housed within said casing and having one end connected thereto to rotate the same, a rotatable element connected to the other end of said spring and adapted to be rotated thereby in an opposite direction, stops for limiting the rotation of said casing and said rotatable element by said spring, said arm being adapted to engage and rotate the casing against the tension of the spring when moved in one direction, and engage and rotate said rotatable element against the tension of the spring when moved in the opposite direction.

2. In a door closing device, the combination of a supporting bracket provided with a stud or spindle, of a spring casing rotatably mounted thereon, a sleeve rotatably mounted on said spindle, a spring housed within said casing having one end connected therewith and the other end connected with said sleeve, said spring tending to rotate said casing and sleeve in opposite directions stops for limiting the rotative movements of said casing and sleeve, and an arm pivotally supported by said bracket and adapted to rotate said casing against the tension of said spring when moved in one direction, and to rotate said sleeve against the tension of the spring when moved in the opposite direction.

3. In a door closing device, the combination of a supporting bracket, a spring casing rotatably supported thereby and having a series of holes in its bottom wall, a spring housed within said casing adapted to rotate the same, an arm pivotally mounted on said bracket and adapted to rotate said casing against the action of said spring, and a stop adapted to be inserted in any one of said series of holes and engage said bracket for limiting the movement of said casing by said spring.

4. In a door closing device, the combination of a supporting bracket, a spring casing rotatably supported thereby and having a series of holes in its bottom wall, a spring housed within said casing adapted to rotate the same, an arm pivotally mounted on said bracket and adapted to rotate said casing against the action of said spring, and a stop pivotally mounted concentrically with the axis of said casing and adapted to enter any one of said series of holes and engage the bracket for limiting the movement of the casing by said spring.

5. In a door closing device, the combina-

tion of a supporting bracket, a spring casing rotatably supported thereby and having a series of holes in the bottom wall thereof, a spring housed within said casing and adapted to rotate the same, an arm pivotally mounted on the bracket and adapted to rotate said casing against the action of said spring, a stop pivotally supported by the bracket concentrically with the axis of said casing adapted to enter any one of said series of holes and engage the bracket for limiting the movement of the casing by said spring, said stop being adapted to be pulled outwardly away from said casing and moved on its pivotal support, and a spring for yieldingly holding said stop in engagement with said casing.

6. In a door closing device, the combination of a supporting bracket provided with a stud or spindle, a spring casing journaled on said stud, a sleeve also journaled on said stud, a spring housed within said casing having one end connected thereto, and the other end connected to said sleeve, said spring being adapted to rotate said casing and sleeve in opposite directions, a stop adjustably connected to said casing and adapted to engage said bracket for limiting the movement of said casing, a stop carried by said sleeve, and a fixed stop engaging therewith, and an arm journaled on said sleeve adapted to engage and rotate the casing against the tension of the spring when moved in one direction and to engage and rotate said sleeve against the tension of the spring when moved in the opposite direction.

7. In a door closing device, the combination of a supporting bracket, provided with a stud or spindle, a spring casing journaled on said stud, a cover for said casing adjustably secured thereto, a sleeve also journaled on said stud and projecting through said cover, a spring housed within said casing having one end connected thereto and the other end connected to said sleeve, said spring being adapted to rotate said casing and sleeve in opposite directions, a stop carried by said casing adapted to engage said bracket for limiting the rotation of said casing, a stop carried by said sleeve and a fixed stop engaging therewith to limit the rotative movement of said sleeve, an arm journaled on said sleeve, a stop on said cover adapted to be engaged by said arm for moving the casing against the tension of the spring, and a stop on said sleeve adapted to be engaged by said arm when moved in the opposite direction for moving said sleeve against the tension of the spring.

8. In a door closing and checking device, the combination of a supporting bracket, an arm pivotally secured thereto, checking mechanism carried by said arm, a rotatable shaft mounted on said arm for operating said mechanism, and suitable connections

between said shaft and said bracket for rotating said shaft when said arm is moved on its suitable support.

9. In a door closing and checking device, 5 the combination of a supporting bracket, an arm pivotally secured thereto, checking mechanism carried by said arm, a rotating shaft mounted on said arm for operating said mechanism, a sprocket wheel mounted 10 on said shaft, a sprocket wheel fixedly mounted on said bracket and an endless chain connecting said sprockets for rotating said shaft when said arm is moved on its pivotal support.

15 10. In a door closing and checking device, the combination of a supporting bracket, an arm pivotally secured thereto, a piston operatively mounted in said arm, a rotatable shaft mounted in said arm adapted to 20 operate said piston, and means connecting said shaft with a fixed portion of said bracket for rotating the shaft when said arm is moved on its pivotal support.

11. In a door closing and checking device, 25 the combination of a supporting bracket, of a hollow arm pivotally secured thereto, checking mechanism mounted within said arm, a shaft rotatably mounted in said arm adapted to operate said checking mechanism, and means connecting said shaft with a fixed portion of said bracket for rotating 30

the shaft when said arm is moved on its pivotal support.

12. In a door closing and checking device, the combination of a supporting bracket, a 35 hollow arm pivotally secured thereto, a reciprocating piston mounted in said arm, a crank shaft also mounted in said arm adapted to reciprocate said piston, and means connecting said shaft with the fixed portion of said bracket for rotating the shaft when said arm is moved.

13. In a door closing and checking device, the combination of a supporting bracket, a hollow arm pivotally secured thereto, a pair 45 of reciprocating pistons within said arm adapted to be moved toward and from each other, a crank shaft operatively connected to said pistons, a sprocket wheel mounted on said shaft, a second sprocket wheel 50 fixedly mounted on said bracket concentrically with the pivotal support of said arm, and an endless chain connecting said sprocket wheels.

In testimony whereof I have hereunto set 55 my hand in presence of two subscribing witnesses.

ADAM H. SULSER.
